UNITED STATES PATENT OFFICE

136,162

DESIGN FOR A FAN PROPELLER

Bert Lee, Hollywood, Calif.

Application May 3, 1943, Serial No. 110,102

Term of patent 14 years

To all whom it may concern:

Be it known that I, Bert Lee, a citizen of the United States, residing at Hollywood, in the county of Los Angeles and State of California, have invented a new, original, and ornamental Design for a Fan Propeller, of which the following is a specification, reference being had to the accompanying drawing, forming a part thereof.

I claim:

The ornamental design for a fan propeller, as shown.

BERT LEE.
